UNITED STATES PATENT OFFICE

ERNEST F. SCHREIBER, OF OMAHA, NEBRASKA

DESIGN FOR A BOOTH

Application filed March 10, 1930. Serial No. 34,806. Term of patent 14 years.

To all whom it may concern:

Be it known that I, ERNEST F. SCHREIBER, a citizen of the United States, residing at Omaha, in the county of Douglas and State of Nebraska, have invented a new, original, and ornamental Design for a Booth, of which the following is a specification, reference being had to the accompanying drawing, forming part thereof.

Figure 1 is a side elevation of a booth showing my new design,

Figure 2 is a side view thereof, the view being taken at a right angle to the showing in Figure 1.

This structure constitutes an independent or complete article of manufacture, and is made and sold as such.

I claim:

The ornamental design for a booth as shown and described.

ERNEST F. SCHREIBER.
